LEVER-OPERATED ELECTRIC SWITCHING DEVICE

John Alfred Chilman, Gloucester, England, assignor to Rotol Limited, a British company

Application March 8, 1943, Serial No. 478,415
In Great Britain December 18, 1941

4 Claims. (Cl. 200—5)

This invention is concerned with electric switching devices of the type comprising a movable contact-element mounted on, or constituted by, a pivoted lever spring-pressed to move in one direction (usually to its "off" position), an actuating-lever separately pivoted and movable to engage and rock the contact-lever against the action of its control-spring into a position in which the actuating-lever locks the contact-lever against return movement under the action of the control-spring. Such switches are ordinarily made so that, and intended to be used in such a manner that, the actuating-lever is moved to the full extent of its movement so that it locks the contact-lever to its locked position.

An object of the invention is to provide a construction by which the switch-device can be readily changed from the permanently-operated type of switch to the "momentary" type, in which the contact is maintained only so long as the lever is pressed, and also to provide certain other improvements for increasing the utility of such a switch-device.

This invention, accordingly, comprises a switch of the type above-described, wherein the portion of the contact-lever engaged by the actuating-lever is so shaped or disposed that locking of the contact-lever takes place only after a predetermined movement of the actuating-lever, and that full engaging electrical contact is effected before this position is reached, and wherein interchangeable means are provided for determining the range of movement of the actuating-lever. This said interchangeable means may constitute cover-plates secured over the switch and slotted to permit the actuating-lever to project through the slot for its actuation, the length of the slot being selected according to the range of movement of the lever which it is desired to have.

According to another feature of this invention, a switch as above-described may be provided with a contact-lever having two separate contactors co-operating with different fixed contacts, and an actuating-lever arranged to move it in one or other direction to engage one or other set of contacts according to the direction of movement of the actuating-lever.

Alternatively, a switch as above-described may comprise two separate contact-levers and a single actuating-lever arranged to move one or other of the contact-levers according to its direction of movement. Preferably, the contact-levers in this case are mounted to swing about a pivotal axis common to both of them but lying on opposite sides thereof, and it will be appreciated that the

range of movement of the actuating-lever in its two directions need not necessarily be the same.

According to another feature of this invention, the actuating-lever may itself be operated by a separate actuating-handle, and the predetermining of the range of movement is applied to the actuating-handle. This construction is particularly adapted for use with ganged switches.

According to another feature of this invention, 10 a ganged switch may comprise a plurality of switches as above-described assembled side by side with their actuating-levers mounted on co-axial sleeves, in combination with a single actuating-handle movable axially to engage selectively any 15 one of the said sleeves to rock it.

In the accompanying drawings:

Figure 1 is a sectional elevation showing the operative parts of a switch according to this invention in the "off" position,

20 Figure 2 is a similar view showing the switch in its momentary "on" position,

Figure 3 is a similar view showing the switch modified to permit it to be set in a permanently "on" position,

25 Figure 4 is a similar view showing a duplex form of the switch illustrated in Figure 1, adapted to control two separate circuits.

Figure 5 is a sectional view of a switch as illustrated in Figure 4 showing it mounted in a standard form of switch casing,

30 Figure 6 is a sectional view on the line 6—6 of Figure 5.

Figure 7 is an elevation, partly in section, of two switches ganged together and operated by a single 35 actuating-handle,

Figure 8 is a sectional view on the line 8—8 of Figure 7.

Figure 9 is a view on the line 9—9 of Figure 7,

Figure 10 is a sectional view of a detail, and

40 Figure 11 is a view similar to Figure 1, showing a modified construction of switch.

Referring first to Figures 1 and 2 which illustrate the simplest form of switch in accordance with this invention, a contact-lever indicated 45 generally by the reference 10 is mounted to swing on a pivot pin 11 and comprises three arms 12, 13, 14. The arm 14 carries a contactor 15 mounted on it by means of an insulator 16, this contactor being adapted to engage a co-operating contact 17. Preferably, the contactor 15 is U-shaped and each of its limbs is adapted to engage one of a pair of contacts 17 so as electrically to couple them together to complete a circuit, this arrangement providing that the contact-lever 10 and its pivotal mounting are not in-

cluded in the electrical circuit controlled by the switch. Conveniently, the lever 10 is itself of U-shaped formation, constituted by two plates which are of the shape represented by 10 in Figure 1, connected by a flat base portion which carries the insulator 16 and the contact 15. The pivot pin 11 extends through the two arms of the lever 10 and an actuating-lever 18 lies between the two arms and carries rollers 19 to engage each of them to operate it. A controlling spring 20 of any convenient form is provided to press the lever 10 towards its "off" position illustrated in Figure 1.

The two arms 12 and 13 of the lever 10 are inclined to one another at about a right angle, and the rollers 19 aforesaid lie between them. The arm 13 which is used to move the switch to its "on" position is so shaped at 21 as to lie closely beside the rollers 19 in the "off" position of the switch so that when the actuating-lever 18 is moved towards the right in Figure 1, it sweeps along the part 21 as shown in Figure 2 to bring the contactor 15 into full electrical engagement with its co-operating contacts 17, but in this position the spring 20 would still be operative to return the switch to its "off" position when the actuating-lever is released, thus constituting a momentary switch by which is meant as above described, a switch in which the circuit is maintained closed only so long as the actuating-lever 18 is manually held in the position shown in Figure 2.

The arm 13 of the lever 10 is further shaped at 22 so that if the actuating-lever 18 be moved somewhat further, to the position illustrated in Figure 3, the surface 22 engages the rollers 19 so as to lock the switch in its "on" position. The shaping of the surfaces 21, 22 to effect the above-described functions consists in inclining them towards one another so that the pressure exerted between the surface 21 and the roller 19 has a component tangential to the line of movement of the rollers 19, whilst the surface 22 is substantially normal to that line of movement.

In this simple form of the switch, the actuating-handle 23 may be formed integrally with the actuating-lever 18, and it projects through a cover-plate 24 which is slotted to permit its movement. As shown in Figures 1 and 2 the slot 25 is of such a length that the handle 23 cannot move further than the position illustrated in Figure 2, so that the switch can be operated only as a momentary switch, since the rollers 19 cannot be moved into engagement with the surface 22 of the lever 10. If it is desired to convert the switch to one which can be permanently operated, the cover-plate 24 is replaced by a similar cover-plate 26 as shown in Figure 3 in which the slot 27 is of greater length, permitting the further movement of the actuating-lever 18. It will be seen, therefore, that in order to provide the two varieties of switch, namely momentary or permanent, it is merely necessary to provide the alternative cover-plates 24, 26, as all the other parts of the switch are identical.

The arm 12 of the lever is provided with a surface 28 which is so positioned as to be engaged by the rollers 19 when the actuating-lever 18 is moved from the position shown in Figure 3 towards its "off" position which is shown in Figure 1. Ordinarily it will not come into engagement with it, since the spring 20 will move the contact-lever 10 away from its engaging position as soon as it is released, but the surface 28 provides for the positive disengagement of the

switch if it should be held frictionally by the contacts 17 against the action of the spring 20.

Figure 4 illustrates a duplex form of the switch illustrated in Figure 1, in which two contact-levers 29, 30 are mounted on a common pivot pin 31. Each of these levers is similar to the lever 10 illustrated in Figure 1, but they are arranged right- and left-handedly respectively, so that their contacts 32, 33 engage the contacts 34, 35 respectively when they are moved by the actuating-lever 18. The controlling spring 20 in this case operates on both levers, each one serving as an abutment when the other is moved. The actuation of each of the levers is effected by surfaces similar to the surfaces 21, 22 of Figure 1, and the surface corresponding to the surface 28 of Figure 3 is so positioned that when the actuating-lever 18 is moved in one direction, for example as shown in Figure 4 to close the contacts 32, 34, the lever 33 is not operated. There is thereby provided a switch with a single actuating-handle 23 which when moved in one direction from its "off" position (see Figure 4), closes the contacts 32, 34 and when moved in the other direction closes the contacts 33, 35, at the same time opening the contacts 32, 34. The range of movement of the actuating-handle 23 is determined by the length of the slot 36 in the cover-plate 37, and it will be appreciated that its length in either direction from the central position may be such as to make either of the switches 32, 33 a momentary switch or a permanent switch. As before, all the operative parts of the switch for either type are identical with one another and it is only necessary to change the cover-plate to obtain any desired combination of switches.

Figures 5 and 6 show a switch of the kind illustrated in Figure 4 mounted in a standard form of casing 38. A U-shaped member 39 secured by a bolt or stud 40 carries the pivot pin 41 for the contact-levers 42, 43 which are U-shaped and interleaved with one another; they each carry the contactors 44, 45 on insulators 46, 47 respectively, and the contactors are arranged to complete the circuit between the contacts 48, 49 and 50, 51 respectively, these contacts preferably taking the conventional form of spring jaws. The pivot pin 41 is retained in place by the side walls of the casing 38 when it and the contact-levers assembled on it have been inserted in the casing.

The casing also comprises a cover-piece 52 to enclose the terminal connections for the contacts, and a separate base portion 53 which carries the actuating-lever 54 and actuating-handle 55; these three portions of the casing are secured together by suitable bolts and the interchangeable cover-plate 56 or escutcheon with the slot 57 to determine the range of movement of the actuating-handle 55 is secured on the casing 53.

Figures 7 and 8 illustrate a construction of ganged switch in which two switches such as are illustrated in Figures 4, 5 and 6 are assembled together and controlled by a single operating-handle. The two switches are mounted in separate casings 58, 59 similar to the casing 38 with all the parts carried thereby, but a separate base portion of the casing 59 is provided to receive the two casings 58, 59. Within this base 60 there is secured a pivot pin 61 upon which there is slidably mounted a sleeve 62 and preferably a controlling spring 63 normally presses the sleeve 62 towards one end of the casing, this spring taking its abutment on a suitable washer 64. The sleeve 62 carries an actuating-handle 65, and surrounding the sleeve are two actuating-lever-

sleeves 66, 67 which carry respectively the actuating levers 68, 69 for the two switches. These two sleeves 66, 67 abut one another endwise and each is slotted at 70, 71 respectively on their abutting faces to accommodate the actuating-handle 65, the lengths of the slots 70, 71 being sufficient to permit the actuating-handle 65 on the sleeve 62 to be moved so as to engage one or other of the sleeves 66, 67; when so engaged, the rocking movement of the actuating-handle 65 rocks one or other of the sleeves 66, 67 and through the actuating-lever 68 or 69 operates the corresponding contact-levers.

Upon the bottom of the complete switch casing there is mounted a cover-plate or escutcheon 72 which is illustrated separately in Figure 9, and this is appropriately slotted to accommodate the movement of the actuating-handle 65. The slot is in the form of a gate which permits the handle 65 to be moved to either of the positions 73, 74 to operate one switch, for example that in the casing 59, or alternatively it may be moved to the right of Figure 9 and then moved to either of the positions 75, 76 to operate the switches in the casing 58 of Figure 7.

In some cases there may be one or more movements of the switch-handle which are not ordinarily required, and in order to provide a safeguard against the switch being accidentally moved to that position, a construction of actuating-handle illustrated in Figure 10 may be used. The sleeve 62 carries an arm 77 rigidly secured on it with an operating handle 78 telescopically mounted on the arm 77 and normally pressed radially inwards by a spring 79. The gate in the cover-plate normally engages the sleeve portion of the operating handle, and the slots 73, 75, 76 are made of a suitable width. The slot 74, however, is made narrower of such dimensions as to accommodate only the arm 77 so that the operating handle can be moved to enter the slot 74 only by withdrawing the handle 78 against the action of the spring 79. The deliberate action thus called for prevents accidental movement of the actuating-handle into the slot 74, such as might occur when moving the handle from the slot 73 to its "off" position.

Figure 11 illustrates a modified form of switch which is shown in its simplest form corresponding to the construction illustrated in Figure 1. In this modification the contact-lever 80 carries an insulated contactor 81 corresponding to the contactor 15 of Figure 1, and is provided with similar cam surfaces 82, 83 on the arm 84 to be operated by the actuating-lever 85, and the modification consists in the provision on the arm 86 of the lever 29 of a contactor 87 to engage a co-operating contactor 88.

The contact-lever 80 is so shaped that when the contactor 81 is in its "off" position, the contactor 87 is in engagement with its co-operating contacts 88 so that one or other of the circuits controlled by the switch is always closed, there being no intermediate position in which both circuits are open. For this purpose the actuating-handle 89 is movable only in one direction in the slot 90, and the length of this slot is selected as hereinbefore described, to provide that the contactor 81 operates either as a momentary switch or as a permanent switch.

In Figure 11 there is shown only one contactor switch 80, but it will be appreciated that the various modifications illustrated in Figure 4 or Figures 5 and 6, or Figures 7 and 8 may all have embodied in them contact-levers similar to that

of Figure 11 carrying two separate contactor elements.

It will be understood that the operating-handle is controlled as to its range of movement by the lengths of the slots in the cover-plate 72, in the manner above described; as shown in Figure 9, the slots 73, 74 permit that particular switch to be moved so that either of its contactors goes to the permanently "on" position, whilst the slots 75 and 76 are shorter so that the other switch is, as regards both of its contactors, a momentary switch. Any desired selection of the length of the various slots may be used according to the requirements of any particular case. The construction of switch illustrated in Figure 7 can be used to control four separate circuits, but the invention is not necessarily limited thereto, since the gate in the cover-plate 72 can be extended to provide any desired number of operating switches for one actuating-handle, it being only necessary to provide suitable axially-disposed slots in the actuating-lever-sleeves to accommodate the axial movement of the handle.

I claim:

- 25 1. A switch comprising a base, a contact on the base, a lever carrying a contact to engage the base contact and pivoted on the base to rock between a position in which the contacts are engaged and one in which they are disengaged, a spring biasing the contact-carrying lever to rock in one direction, an actuating lever pivoted on the base and operable by a movement in one direction about its pivot to rock the contact-carrying lever against the bias of the spring from one position to the other and thereafter by a further movement in the same direction to lock the contact-carrying lever in the latter position, and two alternative gates for the actuating lever, one of which permits it to make its full movement and the other of which permits it to move sufficiently to rock the contact-carrying lever from one position to the other but not to lock that lever.
- 30 2. A switch comprising a base, a contact fixed on the base, a lever carrying a contact to engage the fixed contact and pivoted on the base to rock between a position in which the contacts are engaged and one in which they are disengaged, a spring biasing the contact-carrying lever to rock in one direction, an actuating lever pivoted on the base and operable by a movement in one direction about its pivot to rock the contact-carrying lever against the bias of the spring from one position to the other and thereafter by a further movement in the same direction to lock the contact-carrying lever in the latter position, and two cover plates to be secured to the base alternatively and formed with slots of different length to receive the actuating lever and limit its movement, the slot in one cover being of such length that the lever can move through its full stroke while that in the other cover being of such length as to prevent the lever reaching its locking position.
- 35 3. The combination with two switches each comprising a base, a contact fixed on the base, a lever carrying a contact to engage the fixed contact and pivoted on the base to rock between a position in which the contacts are engaged and one in which they are disengaged, a spring biasing the contact-carrying lever to rock in one direction, an actuating lever pivoted on the base and operable by a movement in one direction about its pivot to rock the contact-carrying lever against the bias of the spring from one position

to the other and thereafter by a further movement in the same direction to lock the contact-carrying lever in the latter position, of a common actuating handle pivoted about a common pivotal axis of the actuating levers of both switches, movable along said axis to engage one or the other actuating levers to operate it when rocked about said axis, and a gate cooperating with the actuating handle to prevent it rocking except when engaged with one only of the actuating levers and to permit it to rock the actuating lever of one switch to its full extent and to restrict its rocking movement when engaged with the actuating lever of the other switch to the extent just short of the movement required to lock the contact-carrying lever in that switch.

4. The combination with two switches each comprising a base, two contacts fixed on the base, two levers pivoted on the base and each carrying a contact to engage a different one of the fixed contacts, spring means biasing both said levers

5 to disengage the contacts, a common actuating lever pivoted on the base to engage one or the other contact-carrying levers depending on the direction in which it is rocked and arranged to rock the lever it engages into its engaged position and then to lock it in that position by a further movement in the same direction, said two switches mounted side by side with the pivots of their actuating levers co-axial, a common actuating handle pivoted about the common pivot of the levers and movable therealong to engage one or the other of them, and a gate having an H-shaped slot through which the actuating handle extends, the branches of which slot are of different lengths, the longer branches permitting the actuating handle to close, and to lock closed, the related contact pair and the shorter branches permitting the actuating handle to close, but not to lock closed, the related contact pair.
